Primary Examiner — Mary Ann Calabrese*(74) Attorney, Agent, or Firm* — Innovation Capital Law Group, LLP; Vic Lin(57) **CLAIM**

The ornamental design for a pegboard, as shown and described.

DESCRIPTION

FIG. 1 is a front elevation view of a pegboard, showing our new design;

FIG. 2 is a rear elevation view thereof;

FIG. 3 is a left elevation view thereof;

FIG. 4 is a right elevation view thereof;

FIG. 5 is a top plan view thereof;

FIG. 6 is a bottom plan view thereof;

FIG. 7 is a cross-sectional view thereof taken along lines 7-7 of FIG. 1;

FIG. 8 is an enlarged detailed view of the encircled area 8 of FIG. 7;

FIG. 9 is a front perspective view thereof; and,

FIG. 10 is a bottom rear perspective view thereof.

The dash-dot-dash lines in FIGS. 7 and 8 represent the bounds of the enlargement taken from FIG. 7 and forms no part of the claimed design.

1 Claim, 7 Drawing Sheets---
